ADHESIVE APPLYING APPARATUS

George L. Rock, Cicero, Ill., assignor to Western Electric Company, Incorporated, New York, N. Y., a corporation of New York

Application January 22, 1931, Serial No. 510,462

5 Claims. (Cl. 91—44)

This invention relates to adhesive applying apparatus, and more particularly to an apparatus for cementing insulating heads to a core.

An object of this invention is to provide a simple, efficient, and practical apparatus for applying a predetermined quantity of adhesive material to a core.

In accordance with the object of the present invention, an apparatus is provided with rotatable chucks for receiving a core to which insulated heads are to be cemented, the chucks being operatively connected to a mechanism for rotating them with the core and heads a predetermined number of revolutions and during the rotation of these members transversely extending jets are disposed in engagement with the core adjacent the heads for simultaneously depositing an adhesive material thereupon. Operatively connected to the mechanism for rotating the chucks is an adhesive supplying mechanism having a combined piston and valve arrangement communicating with each of the jets and operative in timed relation to supply a continuous flow of adhesive material to the core and the insulated heads while the jets are effective.

The invention will be more fully understood from the following description, taken in connection with the accompanying drawings, in which

Fig. 1 is a side elevational view of the apparatus;

Fig. 2 is an enlarged sectional view taken along the line 2—2 of Fig. 1;

Fig. 3 is an enlarged side elevational view of a portion of the apparatus;

Fig. 4 is a fragmentary sectional view of the apparatus, portions thereof being shown in elevation;

Fig. 5 is a sectional view taken along the line 5—5 of Fig. 3;

Fig. 6 is a sectional view taken along the line 6—6 of Fig. 5, and

Fig. 7 is a sectional view taken along the line 7—7 of Fig. 6.

Referring now to the drawings wherein like reference numerals designate similar parts throughout the various views, the numeral 10 designates a housing mounted upon a suitable support or table 11 and having extending therethrough and journaled in the walls thereof a supporting shaft 12 upon which is mounted a relatively large gear 13. Mounted upon the shaft 12 adjacent the gear 13 is a ratchet wheel 14 which is keyed to the gear and arranged to rotate therewith upon the shaft. Adjacent the ratchet wheel 14 and mounted upon the shaft 12 is a lever 15

having transversely extending portions 16 and 17. A spring pressed pawl 18 is pivotally mounted upon the portion 16 of the lever 15 and has its free end disposed in engagement with the ratchet wheel 14 so as to engage teeth 19 formed upon the periphery of the ratchet wheel. Secured to the outer end of the portion 16 of the lever 15 is a connecting rod 22 extending downwardly and into a cushioning unit 23 (Fig. 1), wherein it is adjustably secured in place by a lock nut. 5 The cushioning unit 23 includes a compression spring 24 in engagement with which one end of a plunger 25 is disposed, the other end of the plunger being pivotally connected to an arm 26 which is keyed to a shaft 27. A bracket 28 secured to the support 11 provides a pivotal support for the shaft 27 and also supports an adjustable stop 29 into engagement with which a weighted lever 30 is arranged to be moved. An actuating lever 32 having one end fixed to the shaft 27 and the other end provided with a pedal 33 constitutes a means for rotating the shaft 27 and actuating the arm 26, the cushioning unit 23, the connecting rod 22, the lever 15, the pawl 18, and the ratchet wheel 14 for imparting a rotary 25 movement to the gear 13.

Rotatably mounted in the housing 10 and having one end extending therethrough is a chuck rotating shaft 38 (Fig. 5), having mounted or formed thereon a pinion 39 which interengages the gear 13 and is arranged to be rotated thereby. Integral with the shaft 38 is a stop arm 40 rotatable with the shaft and arranged to engage the portion 17 of the lever 15 for stopping the rotation of the shaft 38 at a predetermined position and 35 after a predetermined number of revolutions. A driving chuck 41 is fixed to the outer end of the shaft 38 and is formed in general contour to receive and hold against displacement one end of a core 42 to which spaced insulating heads 43 40 and 44 are to be cemented.

In alignment with the shaft 38 and at a spaced position from the driving chuck 41 is a driven chuck 45 rotatably mounted in a sleeve 46 which is slidably disposed in a bracket 47 and normally urged inwardly by a spring 48 which is housed in the bracket 47. The driven chuck 45 has its inner surface recessed as at 49 to receive one end of the core 42, the other end of the core being receivable in the driving chuck 41.

The outer end of the sleeve 46 is slit as at 55 and receives a chuck actuating lever 56 pivotally secured to the sleeve and fulcrummed at 57. The upper end of the lever 56 has an aperture 58 through which a connecting rod 59 extends, the 55

connecting rod having an adjustable collar 60 mounted thereupon in engagement with an arcuate shaped end of the lever. The inner end of the connecting rod 59 is pivotally connected to the upper end of a cam lever 65 which is pivotally mounted at 66 (Fig. 3), and carries a roller 67 at the lower end thereof, the roller 67 being arranged to be engaged by a cam 69 carried by and movable with a lever 70. The lever 70 is fixed to the outer end of the shaft 12 and has a transversely extending pin or finger 71 arranged to engage a lifting lever 72, which is carried pivotally by a supporting bracket 73 and has a finger portion 74 disposed in engagement with an upwardly extending member 75 secured to a cementing unit 76 (Fig. 6). The bracket 73 is U-shaped in general contour (Figs. 5, 6 and 7), the leg portions 80 and 81 extending downwardly in spaced relation from a supporting bar 82 which supports the brackets 47 and 73 and extends through a boss on the housing 10 where it is held by pins or the like.

The cementing unit 76 has conical shaped recesses 90 and 91 (Fig. 7) for receiving conical shaped ends of supporting pivots 92 and 93, respectively, the pivot member 92 having a reduced portion receivable in an aperture in the leg portion 80 while the pivot member 93 is provided with external threads and receivable in a threaded aperture in the leg portion 81. Passageways 94 and 95 in the pivot members 92 and 93 communicate with passageways 96 and 97, respectively, in the cementing unit 76, the passageways 96 and 97 in the cementing unit extending forwardly (to the right Fig. 7), and communicating with passageways in a head portion 98 which constitutes a part of the cementing unit 76 together with transversely extending jets 99 and 100, the jets having longitudinal extending passageways communicating with the passageways in the head portion 98. The forward end of the cementing unit 76 is normally urged downwardly about the pivot members 92 and 93 (Figs. 5 and 6) by spiral tension springs 105, the movement of the cementing unit being controlled by the lifting lever 72.

The supply unit for the adhesive material consists of a casing 110 (Figs. 1, 3 and 5) having valve piston units for forcing a continuous supply of adhesive material to each of the jets 99 and 100. These valve piston units, indicated generally at 111 and 112 (Fig. 5), are identical in construction and a description of one will apply equally well to them both. With the unit 111 (Fig. 3) there is shown a vertically extending valve piston 115, the lower end being hollow as at 116 and having elongated apertures 117 and 118 extending through the wall of the valve piston and communicating with the hollow portion 116. The lower end of the valve piston 115 is slidably receivable in a cylinder 119 which has oppositely disposed passageways 120 and 121 extending therefrom, the passageway 120 communicating with a supply chamber 122 which communicates with the interior of the casing 110, while the passageway 121 communicates with a valve 123 in a supply line 124. The upper end of the valve piston 115 extends through a cover 130 of the casing 110 and has fixed thereto a gear 131 above which there is a reduced portion 132 upon which is disposed a collar 133. The gear 131 of the unit 111 is disposed upon one side of a valve rotating bar 134 (Figs. 1 and 2) and meshing with teeth 135 formed in the valve rotating bar, while a

gear 136 for the unit 112 is positioned on the opposite side of the valve rotating bar and interengages the teeth 135 upon that side of the bar. The valve rotating bar 134 is allowed to move longitudinally between pairs of vertically extending guides 137 and 138 and is limited in its longitudinal movement by a pin 139 (Fig. 3) which extends upwardly from the cover 130 into an elongated slot 140 in the bar.

The collar 133 is pivotally connected to one end of a bracket 145 which is rigidly secured to a piston moving lever 146 and which has an adjusting screw 147 extending through a threaded aperture therein and resting upon a shoulder 148 of the cover 130. The lower end of the lever 146 is operatively connected to a pull rod 150 which extends through the cover 130 and an expansion spring 151 where the lower end thereof receives a nut upon which the spring rests. The spring 151, together with a portion of the pull rod 150 extending therethrough, is encased in a cylinder 152 which is carried by the cover 130 and extends downwardly into the casing 110. The upper portion of the lever 146 extends forwardly and downwardly providing a cam surface 155 merging into a notch 156. The cam surface 155 rides upon a cam roller 157 carried by a piston moving bar 158 while the notch 156 is arranged to receive a latch 159 for holding the lever 146 upwardly to position the cam surface free of engagement with the cam roller and thus position the lever in an inoperative position.

The piston moving bar 158 is movable longitudinally between the pairs of guides 137 and 138 and positioned upon spaced rollers 160 which are disposed between the bar 158 and the bar 134. Situated adjacent the cam roller 157 and carried by the piston moving bar 158 is a lug or projection 162 in engagement with which retaining latches 163 and 164 are arranged to be moved by an expansive spring 165, the ends of which are connected thereto. The latches 163 and 164 are disposed between the guides 137 and 138, respectively, and pivotally secured thereto while projections thereof extend downwardly and are arranged to be engaged by upwardly extending cams 167 carried by the bar 134. The cams 167 are in the form of lugs integral with the valve rotating bar 134 and disposed at spaced positions as shown in Fig. 2.

A means for moving the bars 134 and 158 consists of a double yoke 170, the forked ends of which straddle rollers 171 and 172 carried by the forward ends of the bars. A rocking lever 173 pivotally mounted at 174 on the casing 110 has one end thereof pivotally connected to the yoke 170 adjacent the center of the yoke, the other end being operatively connected to a draw bar 175 and urged forwardly by an expansive spring 176. The draw bar 175 is pivotally connected to the lever 70, thus connecting the adhesive material supplying means with the work supporting and rotating means so that they will operate simultaneously.

In the operation of the apparatus the pedal 33 is normally in a forward position ready to be moved to the left and into the position shown in Fig. 1. While in the normal or forward position, the chuck 45 is held in its open position; that is, 70 in its position farthest from the chuck 41 by the cam 69 (Fig. 3) which is positioned in engagement with the roller 67, holding the upper end of the cam lever 65 in its farthest position to the right (Fig. 5), and by the aid of the connecting 75

rod 59 holding the upper end of the chuck actuating lever 56 in its farthest position to the right and the lower end of the chuck actuating lever in its farthest position to the left, which, due to its connection with the driven chuck 45, holds the driven chuck away from the driving chuck 41. While in this position, the operator may insert the core 42 so that one end will be positioned in the chuck 41 and the other end positioned in the 10 chuck 45. The pedal 33 may then be moved to the left and into the position shown in Fig. 1, moving the weighted lever 30 to the upper position shown and moving the connecting rod 22 upwardly. Due to the connection of the pawl 18 with a tooth 19 of the ratchet 14, (Figs. 3, 4 and 5), the ratchet wheel will be rotated a predetermined amount, thus rotating the gear 13 and imparting movement to the levers 15 and 70. The rotation of the gear 13, due to its engagement with the pinion 39 of the shaft 38, will rotate the shaft 38 through two complete revolutions, thus imparting a similar rotation to the core 42. The portion 17 of the lever 15 is arranged to be positioned adjacent the shaft 38 so 25 that the stop arm 40 will engage therewith and stop the rotation of the chuck 41 at a desired position.

As soon as the gear 13 starts its rotative movement, the lever 70 (Figs. 3 and 5), is moved to swing the cam 69 from beneath the roller 67 of the cam lever 65, allowing the spring 48 to move the chuck 45 inwardly and grip the adjacent end of the core 42 and at the same time the pin 71, which has held the lifting lever 72 in such a position as to hold the cementing unit 76 in its upper or inoperative position, releases the lifting lever 72 and allows the springs 105 to move the cementing unit into a position so that the jets 99 and 100 will rest upon the core 42. As soon as the 40 jets engage the core 42, adhesive material is forced through the jets and upon the core and the insulating heads 43 and 44 due to the actuation of the units 111 and 112. The units 111 and 112 are actuated simultaneously and as the lever 45 173 is actuated due to the movement of the lever 70 to move the upper end of the lever 173 inwardly, movement is first imparted to the piston rotating bar 134 moving it to the left (Fig. 3) between the gears 131 and 136 of the valve pistons 50 113, and rotating them in opposite directions which rotation moves the apertures 118 into communication with the passageways 121, the valves 123 and the supply lines 124. The piston moving bar 158 is held against inward movement by the 55 latch 163 engaging the lug 162 until the cam 167 which is positioned at the right of the projection of the latch moves the latch free of the lug 162, this occurring after the valve pistons have been rotated. The inward movement of the piston moving bar 158 moves the rollers 157 with respect to the levers 146, thus allowing the spring 151 to move the levers 146 downwardly rocking upon the ends of the adjusting screws 147 and moving the valve pistons 115 downwardly. During the movement of the valve pistons 115, downwardly, the adhesive material which has been previously drawn into the cylinders 119 by upward movement of the valve pistons 115 as described herein-after will be forced through the apertures 118, the 60 passageways 121, the valves 123, the supply lines 124, through the pivot members 92 and 93, through the passageways 96 and 97 in the cementing unit 76 and through the jets 99 and 100, where it will be deposited upon the core 42 adjacent the insulating heads 43 and 44 and upon the

insulating heads adjacent the core during the rotation thereof. The operative connection of the various actuating parts are such that at the beginning of the movement of the lever 32 the chuck 45 will be freed and allowed to be moved inwardly by the spring 48, the cementing unit 76 will be freed, by movement of the lifting lever 72, so that the jets 99 and 100 may rest upon the core 42 and at the same time the valve pistons 115 will be rotated to move the apertures 118 into communication with the passageways 121. During the rotation of the gear 13 by the actuation of the lever 32, the chuck 41 together with the core 42, the insulating heads 51 and 52 and the chuck 45, will be rotated through two complete revolutions during which time a continuous flow of the adhesive material is applied to the core and the insulating heads.

Upon releasing the lever 32, the weight lever 30 will move the foot lever 32 forwardly, thus 20 moving the connecting rod 22 downwardly and rotating the lever 15, the shaft 12 and the lever 70 into their normal positions. When the lever 15 is moved into its normal position, the pawl 18 passes beyond a tooth 19 of the ratchet 14 ready 25 to rotate the sprocket when the foot lever 32 is again actuated. During the movement of the lever 70 into its normal position, the pin 71 will engage and move the lifting lever 72, moving the cementing unit 76 upon the pivot members 92 and 30 93 and against the tension of the springs 105 to lift the nozzles 99 and 100 free of the core 42. The movement of the lever 70 will also move the cam 69, which is affixed to the lever 70, into engagement with the cam roller 67 and actuate the 35 cam lever 65, the connecting rod 59, the chuck actuating lever 56, to move the chuck 45 outwardly and free the part which has been cemented. At the beginning of the movement of the lever 32 toward its normal position, the lever 173 40 will be actuated first to impart movement to the piston rotating bar 134 moving it to the right (Fig. 3) to rotate the valve pistons 115 so as to position the elongated apertures 117 in communication with the passageways 120. The piston 45 moving bar 158 is held against movement toward the right (Fig. 3) by the latch 164 engaging the lug 162 until the pin 168 engages and moves the projection 166 of the latch sufficiently to free the latch from the lug. Upon being freed by the 50 latch, the piston moving bar 158 will be moved outwardly, moving with it the rollers 157 which will engage the cam surfaces 155 of the levers 146 and move the levers upwardly, during which movement the valve pistons 115 will be moved 55 upwardly, drawing adhesive material from the supply chamber 122 into the cylinder 119. The adhesive material supplying units therefore are made in readiness to force adhesive material to the jets 99 and 100 during the movement of the 60 lever 32 into its normal position.

Although the invention has been described in connection with one particular type of article to be treated, it is to be understood that the apparatus may be adapted to apply material to different types of articles without departing from the spirit and scope of the present invention.

What is claimed is:

1. In a machine for securing spool heads to cores, spaced nozzles for applying adhesive material to the juncture of the heads and core, means for rotating the heads and core, and means operated in timed relation therewith for ejecting a predetermined quantity of the adhesive material from each nozzle. 75

2. In a material applying apparatus, supporting means for a core having spaced heads thereon, means for imparting a rotative movement to the core, means for applying material upon the core at the juncture of the heads therewith during the rotation thereof, means for stopping the rotation of the core, and means for moving the supporting means free of the core.
3. In a material applying apparatus, a supporting means for an article, an actuating member movable in more than one direction means rendered effective by the movement of said member in one direction for imparting a rotary movement to the article, a material applying means, means for moving said material applying means into engagement with the article during the rotation thereof, and means rendered effective by the movement of said actuating member in another direction for simultaneously moving said material applying means away from the article and moving said supporting means free of the article.
4. In a material applying apparatus, a sup-

porting element for an article, a material applying means, a movable actuating means, means rendered effective by one movement of said actuating means for imparting rotary movement to the article and normally restrained spring means rendered effective by said movement of said actuating means for moving said material applying means into engagement with the article.

5. In a material applying apparatus, a supporting means for an article, a material applying means, a movable actuating means, means rendered effective by one movement of said actuating means for imparting rotary movement to said supporting means and the article and moving said material applying means into engagement with the article, means rendered effective at the end of said movement of said actuating means for stopping rotation of said supporting means and means for moving said material applying means free of the article.

GEORGE L. ROCK.
